MANIFOLD SILENCER

Roland B. Bourne, West Hartford, and Arthur E. Chase, Elmwood, Conn., assignors to The Maxim Silencer Company, Hartford, Conn., a corporation of Connecticut

Original application May 5, 1945, Serial No. 592,196. Divided and this application November 16, 1948, Serial No. 60,294

7 Claims. (Cl. 181—40)

1

This invention relates to improvements in silencers particularly intended to be attached directly to the exhaust ports of an internal combustion engine without the intervention of a manifold. In other words, the silencer acts as a manifold as well as performing its usual functions. Such devices are of particular value in connection with Diesel railway locomotives, in which space is at a premium and an exhaust manifold must be used in any case. Ordinary types of silencer are not fitted for this type of work.

The present application is a division of our prior application Serial No. 592,196, filed May 5, 1945, now Patent No. 2,513,229, issued June 27, 1950.

The invention will now be described with relation to the accompanying drawings in which:

Fig. 1 is a section, on line 1—1 of Fig. 2, of one embodiment of the invention;

Fig. 2 is a section on line 2—2 of Fig. 1;

Fig. 3 is a section, on line 3—3 of Fig. 4, of a modification;

Fig. 4 is a section on line 4—4 of Fig. 3;

Fig. 5 is a section, on line 5—5 of Fig. 6, of a further modification;

Fig. 6 is a section on line 13—13 of Fig. 5;

Fig. 7 is a longitudinal section showing a modification of the construction shown in Figs. 1 and 2;

Fig. 8 is a section, on line 8—8 of Fig. 9, showing a further modification;

Fig. 9 is a section on line 9—9 of Fig. 8;

Fig. 10 is a section, on line 10—10 of Fig. 11, of a modification using a slanting partition;

Fig. 11 is a section on line 11—11 of Fig. 10;

Fig. 12 is a section, on line 12—12 of Fig. 13, of a modification using a conical partition; and

Fig. 13 is a section on line 13—13 of Fig. 12.

In general silencers constructed in accordance with the present invention are characterized by an elongated shell into one side of which inlet pipes may enter directly from the ports of the engine. A longitudinal partition, which may assume various forms, divides the casing into two chambers separated transversely of the casing, into one of which the inlet pipes enter and into the other of which enters one or more exhaust pipes from either the side or the end of the casing depending upon the conditions under which the silencer is to be installed. One or more transfer conduits pass, in a direction approximately parallel to the axis of the cylindrical shell of the silencer, from the inlet to the exhaust chamber in such a way that the gas is not allowed to pass directly from the inlet pipes into the transfer

pipes or from the latter into the exhaust pipes, but so that expansion of the gas and a breaking up of the pulses occur in the two chambers.

Figs. 1 and 2 show three inlet pipes 38 inclined within the silencer so as to discharge towards one end of the inlet chamber 39. This chamber is separated from the outlet chamber 40 by a pair of reversely curved arcuate partitions 41 and 42 each extended substantially to the center of the silencer and joined by a lune-shaped partition 43. Through this partition pass longitudinally disposed transfer tubes 44, which may be of differing sizes as shown. The partitions 41, 42 and 43 are preferably so disposed as to permit the transfer tubes to open into that end of the inlet chamber toward which the inlet pipes 38 are directed. An outlet pipe 45 extends longitudinally through end header 46, opening towards that end of the outlet chamber 40 into which the transfer tubes open. A modification of this structure is shown in Fig. 7 in which the inlet pipes 47 and the partitions 48, 49 and 50 are arranged so that the transfer tubes 51 open into that end of the inlet chamber 52 toward which the inlet gases are directed. The outlet pipe 53, however, is in this instance positioned to open into the opposite end of the exhaust chamber 54 from that into which the transfer tubes open. This gives a longer gas flow in the outlet chamber and a double reversal of flow which in some instances increases the silencing effect. These two constructions are of value in increasing the permissible length of the transfer tubes, which should be a substantial fraction of the length of the silencer as shown.

Figs. 3 to 6 represent two forms of a construction similar in purpose to those of Figs. 1, 2 and 7 but with the passage of the transfer tubes from one side to the other of the partition obtained by offsetting the tubes rather than the partition. Referring first to Figs. 3 and 4, the cylindrical casing 63 is divided by a longitudinally extending arcuate partition 64 into an inlet chamber 65 and an outlet chamber 66. Inlet pipes 67 extend into the former chamber and outlet pipes 68 extend into the latter. A series of transfer tubes 69 are offset at an intermediate point so that they may pass through the partition and yet remain generally parallel to the axis of the casing. In the form shown in Figs. 3 and 4 the tubes are all bent in the same direction, while the tubes 70 in Figs. 5 and 6 are bent alternately in opposite directions so that the gas flow is from both ends of the inlet chamber to both ends of the outlet chamber rather

than from one end of the former to one end of the latter as in Figs. 3 and 4.

A manner of forming the partition so as to avoid the necessity of using separate transfer tubes is shown in Figs. 8 and 9. In this instance the partition is formed of two oppositely curved overlapping plates 71 and 72 welded together where they touch. Due to the reverse curvature a passage 73 is formed between the overlapping portions of the plates, and by having the plates shorter than the casing 74 this passageway is made to open at one end into the inlet chamber 75 and at the other into the outlet chamber 76. It will be understood in this and other forms that the inlet and outlet conduits may be arranged in any desired way.

It is not necessary that the partition be arcuate as in the forms previously described. Thus in Figs. 10 and 11 the partition 77 is made of a flat sheet but is arranged on a slant so that the transfer tubes 78 may pass through it and remain parallel to the axis of the casing. In Figs. 12 and 13 the partition 79 is conical and the transfer tubes 80 are parallel to the axis as before. While this form is restricted to cases where the exhaust pipe 81 can extend longitudinally of the locomotive it has the advantage that hot gas from the inlet pipes 82 heats the entire casing and not just one transverse side of it, so that any tendency of the casing to buckle on a longitudinal curve is avoided.

We claim:

1. A manifold silencer comprising a generally cylindrical casing, a longitudinally extending platelike partition within the casing dividing it into laterally adjacent chambers, a plurality of inlet conduits opening laterally of the casing into one of said chambers, an outlet conduit opening into the second of said chambers, and at least one conduit extending through the central part of the partition in a direction generally parallel to the axis of the casing and opening at opposite ends into said chambers.

2. A manifold silencer comprising a generally cylindrical casing, a longitudinally extending partition within the casing dividing it into laterally adjacent chambers, a plurality of inlet conduits opening laterally of the casing into one of said chambers, an outlet conduit opening into the second of said chambers, and at least one conduit extending through the partition in a direction generally parallel to the axis of the casing, said partition and conduit being deformed relative to each other to permit the conduit to lie parallel to the axis on both sides of the partition.

3. A manifold silencer comprising a generally cylindrical casing, a longitudinally extending partition within the casing and having an offset portion at a point intermediate its length, a plurality of inlet conduits opening laterally of the casing into one of said chambers, an outlet conduit opening into the second of said chambers, and at

least one conduit lying substantially parallel to the axis of the casing and passing through the offset portion of the partition.

4. A manifold silencer comprising a generally cylindrical casing, a longitudinally extending partition within the casing, a plurality of inlet conduits opening laterally of the casing into one of said chambers, an outlet conduit opening into the second of said chambers, and at least one conduit lying generally parallel to the axis of the casing and offset intermediate its length to pass through said partition.

5. A manifold silencer comprising a generally cylindrical casing, a pair of oppositely curved longitudinally extending plates secured to the interior of the casing and to each other to form a partition dividing the casing into two laterally adjacent chambers, said plates each extending from one end of the casing past a portion of the other plate part way to the other end of the casing to form between them a conduit extending in a direction generally parallel to the axis of the casing through said partition and opening at opposite ends into said chambers, a plurality of inlet conduits entering one of said chambers, and at least one outlet chamber entering the other of said chambers.

6. A manifold silencer comprising a generally cylindrical casing, a longitudinally extending platelike partition inclined with respect to the axis of the casing and extending from one end to the other of the casing to divide it into two laterally adjacent chambers, a plurality of inlet conduits opening laterally of the casing into one of said chambers, at least one outlet conduit opening into the second of said chambers, and at least one conduit extending through the central part of the partition in a direction generally parallel to the axis of the casing and opening at opposite ends into said chambers.

7. A manifold silencer comprising a generally cylindrical chamber, a conical platelike partition extending longitudinally from one end to the other of the casing to divide it into two laterally adjacent chambers, a plurality of inlet conduits opening into one of said chambers, at least one exhaust conduit entering the other of said chambers, and at least one conduit extending through the central part of the partition in a direction generally parallel to the axis of the casing and opening at opposite ends into said chambers.
